Patented May 11, 1915.

UNITED STATES PATENT OFFICE.

WILLIAM DOWLING AND WILLIAM A. SCHROEDER, OF ST. LOUIS, MISSOURI, ASSIGNEES
TO MESKER BROTHERS IRON COMPANY, OF ST. LOUIS, MISSOURI, A CORPORATION
ON MISSOURI.

METALLIC STAIR CONSTRUCTION.

1,138,642.

Specification of Letters Patent. Patented May 11, 1915.

Application filed May 25, 1914. Serial No. 440,778.

To all whom it may concern:

Be it known that we, WILLIAM DOWLING and WILLIAM A. SCHROEDER, citizens of the United States, residing at the city of St. Louis, State of Missouri, have invented a certain new and useful Improvement in Metallic Stair Construction, of which the following is a full, clear, and exact description, such as will enable others skilled in the art to which it appertains to make and use the same, reference being had to the accompanying drawings, forming part of this specification.

Our invention relates to metallic stair construction, and has for its principal object the provision of a very firm, close and rigid connection between the treads and risers and stringers of the stairs.

A further object is to greatly reduce the cost of metallic stair construction.

Figure 1 is a fragmentary sectional view of a portion of a stringer and a tread illustrating a feature of our invention. Fig. 2 is a vertical section through a tread, showing portions of the risers and a stringer. Fig. 3 is a detail illustrating a joint between a stringer and a tread. Fig. 4 shows a modified form of tread. Fig. 5 is a section of the same illustrating the joint between the tread and stringer. Fig. 6 is a modification illustrating the finish of a joint for a plain metallic tread.

By reference to the accompanying drawing, it will be understood that 1 represents a stringer of the stair construction, and 2 the tread. As illustrated in Fig. 2, it may be desirable to have the risers 4 formed integral with the subjacent tread and secured to the next higher tread by suitable means 5.

In forming the connection between the stringers and treads, heretofore it has been the practice to use angle irons to which these parts are riveted. With this form of construction, it is practically impossible to secure a tight butt joint between the end of the tread and riser and the stringer, with the result that the stairs are inclined to be wobbly, and the space left provides lodgment for dirt, and a place of ingress for water, which renders the stairs leaky and the members subject to rusting out.

In our improved construction, the stringers 1 are pierced with apertures, preferably

two, as illustrated in Fig. 2, just below the level of each tread, which apertures are adapted for the reception of an angle bolt 6. The treads are likewise pierced with apertures 7 which are adapted to receive the upturned end 6^a of the angle bolt. In the angle, the bolt is provided with a notch 6^b of height sufficient to just receive the thickness of the tread, and of depth sufficient to secure a bite or purchase thereon.

In assembling the stairs, the bolts are placed in the apertures of the stringers and the nuts started thereon. The treads are then laid on over the ends of the bolts, and the nuts then screwed up tight, causing the bolts to engage the tread in their notches, and draw the tread and stringers closely together, forming an absolutely tight butt joint, which for all practical purposes is water proof when the parts are properly shaped. The bolt provides a support for the tread and riser, and the notch holds the tread firmly down on the horizontal portion of the bolt and prevents its buckling away under the compression resulting from the tightening of the nut. In case the stairs are to be finished with concrete or composition treads, as illustrated in Figs. 1 and 2, the plastic composition is then put in, covering and encompassing the upwardly extending ends of the bolts. When the composition sets, it is thus interlocked with both the stringers and the tread by virtue of its engagement with the bolts.

While we have shown a structure employing but four bolts to each tread, two at each end, it is obvious that more bolts may be employed if desired.

In Figs. 4 and 5, we have illustrated a modification in which channels 2^a are stamped in the tread, and the bolts laid in the channels. This construction gives a greater bearing area between the ends of the treads and the stringers.

In Fig. 6 is illustrated a method in which the bolt may be finished by a nut 8 screwed on to the upwardly projecting end, which construction may be employed in instances wherein a concrete tread is not used on top of the metallic tread.

This form of construction secures a very rigid stair structure, as the stringers, treads and risers may be drawn together and held

under tension which prevents their webbling. Furthermore, if it becomes necessary through contraction of the parts due to temperature changes, the nuts may be further tightened so as to maintain the rigidity of the structure. This construction greatly decreases the cost of such structures, as it does away with the labor of riveting and the cost of angles and other supporting parts.

10 What we claim is:

In a stair structure of the sort described, the combination with a stringer and a tread portion, having a channel pressed therein adjacent its end, of a headless bolt seated in said channel and passing through the

stringer, one end of said bolt being bent upwardly and extending through the tread at the inner end of the channel therein, there being a slot formed in the upwardly bent 20 end of the bolt, which slot receives a portion of the tread, and means coöoperating with the other end of said bolt for drawing said tread and said stringer together.

In testimony whereof we hereunto affix 25 our signatures in the presence of two witnesses, this 20th day of May, 1914.

WILLIAM DOWLING

WILLIAM A. SCHROEDER.
